Daniel E. Paris, of Troy, New York.
Letters Patent No. 131377. Dated Dec. 18th 1878.
Design for a Stove plate.

The schedule referred to in these Letters Patent and making part of the same.

To all whom it may concern:

Be it known that I, Daniel E. Paris, of the City of Troy, in the County of Rensselaer and State of New York, have invented or produced a new and original ornamental Design for Stove Plates, and I do hereby declare that the following is a full and exact description thereof, reference being had to the annexed photographic drawing of a stove plate embodying my said ornamental design.

This new ornamental design for stove plates consists of the arrangement, upon the middle portion of a parcel A, of a certain compound ornament, composed of two tapered, reverse-curved, upright side-horns b, b, with twisted tapering pendants c, c, in the ends; a central hanging and clinging scroll-plate covering d, d, d; and a crown e, e, having a central tapering twisted pendant f; all shaped and disposed together as shown by the annexed photographic drawing.

What I claim as new and of my invention or production and desire to secure by Letters Patent is the ornamental design for a stove plate as shown and described.
